(57) **CLAIM**

The ornamental design for a helmet bag, as shown and described.

DESCRIPTION

FIG. 1 is an isometric view of a helmet bag hereof;
FIG. 2 is a first side elevational view of a helmet bag hereof;
FIG. 3 is a front elevational view of a helmet bag hereof;
FIG. 4 is a rear elevational view of a helmet bag hereof.
FIG. 5 is a bottom plan view of a helmet bag hereof; and,
FIG. 6 is a top plan view of a helmet bag hereof.

The design is a bag for helmets intended for carrying any helmet, such as a sports helmet. Examples are helmets for motorsports (automobiles, motorcycles, water and air sports, cycling, skiing, skating, extreme sports (rafting, mountain-eering), equestrian sports, etc.).
The broken lines shown in the drawings are understood to represent stitching.
